CLAIM

The ornamental design for a massage spike appliance, as shown and described.

DESCRIPTION

FIG. 1 is a front perspective view of a massage spike appliance, showing my design.

FIG. 2 is a rear perspective view thereof.

FIG. 3 is a front elevation view thereof.

FIG. 4 is a rear elevation view thereof.

FIG. 5 is a left side elevation thereof.

FIG. 6 is a right side elevation thereof.

FIG. 7 is a top plan view thereof.

FIG. 8 is a bottom plan view thereof; and,

FIG. 9 is a perspective view showing a state of use of the massage spike appliance with other massage spike appliances.

The broken lines in the drawings depict environmental structure and boundaries and form no part of the claimed design.
